CLAIM

The ornamental design for a front face of a vehicle steering wheel, as shown and described.

DESCRIPTION

FIG. 1 is a front perspective view of a front face of a vehicle steering wheel showing my new design with the electrical power switch turned on in the on position;

FIG. 2 is a front elevational view thereof;

FIG. 3 is an enlarged front elevational view thereof showing the central portion of the front face of a vehicle steering wheel;

FIG. 4 is another front perspective view thereof with the electrical power switch turned off in the off position;

FIG. 5 is a front elevational view of FIG. 4; and,

FIG. 6 is an enlarged front elevational view of FIG. 4 showing the central portion of the front face of a vehicle steering wheel.

The claimed design is directed to a front face of a vehicle steering wheel that can be turned ON and OFF.

The broken lines shown throughout the drawing views are for illustrative and environmental purposes of showing electrical power elements that can display visual information but, does not form part of the claimed design.
